VANITY MIRROR

Laurice D. Ely, Los Angeles, Calif., assignor to Elco Products Corp., Santa Monica, Calif., a corporation of California

Filed Mar. 14, 1966, Ser. No. 1,459

Term of patent 14 years

(Cl. D86—10)

I claim:

The ornamental design for a vanity mirror, substantially as shown.
